FIG. 1.

FIG. 2.

FIG. 3.

UNITED STATES PATENT OFFICE

2,046,311

DISHWASHING MACHINE

Haskell C. Carter, Portland, Oreg.

Application August 4, 1934, Serial No. 738,499

8 Claims. (Cl. 141—9)

This invention relates generally to washing machines, and particularly to a dish washing machine.

The main object of this invention is the construction of an exceedingly simple and efficient form of dish washing machine which can be fabricated at a relatively low cost.

The second object is to produce a machine which will wash dishes efficiently in a minimum amount of time without the exercise of skill on the part of the operator.

The third object is to so construct the dish washer that it can be used in conjunction with the ordinary kitchen sink and that the dishes can be placed therein in an economical manner and that a lateral surging action will be made to take place parallel to the lines in which the plates and flat dishes are set within the washer.

The fourth object is to so construct the washer that the outlets for the air line are so disposed as to prevent their interfering with the normal operation of the machine, and at the same time to serve as handles for the machine.

These, and other objects, will become more apparent from the specification following as illustrated in the accompanying drawing, in which:

Fig. 1 is a longitudinal section through the device.

Fig. 2 is a perspective view looking upwardly into the dish container.

Fig. 3 is a vertical section taken along the line 3—3 in Fig. 1.

Similar numbers of reference refer to similar parts throughout the views.

Referring in detail to the drawing, there is shown a bottomless container consisting of the front and rear walls 10 and 11, the horizontal top 12 and the sloping top side portions 13 and 14, the former of which is provided with a transparency 15. The end walls 16 are provided on their lower edges with rubber feet 17 which rest upon the sink bottom 18. The walls 10 and 11, however, do not extend to the sink bottom 18 but their lower edges 19 are raised above same.

Within the top 12 is formed a dome 20 at the upper end of which is disposed a fan chamber 21 which communicates with the dome 20 by means of the opening 22, and the body of the container communicates directly with the interior of the dome 20. Within the fan chamber 21 is mounted a fan 23 which is driven by an electric motor 24 mounted on the top side of the dome 20.

The fan chamber 21 communicates by way of the openings 25 with the air outlet ducts 26 whose outlet ends 26—A also serve as handles by means of which the entire container can be placed in the sink or removed therefrom.

It will be noted that the outlets 26—A are on the opposite ends 16 which extend to the sink bottom 18. This is very important, as to place these outlets on the open side of the container 10 or 11 would interfere with the operation of the device. This is due to the fact that since a high velocity is imparted to the air by the fan 23, to discharge it toward the front or back edges 19 would drive the water away from this portion of the container, while by discharging the air toward the bottom of the ends 16 the water is driven toward the edges 19.

Within the container is disposed a wire frame basket 27 having pockets formed between the wires 28 which are parallel to the end walls 16. These pockets are adapted to receive plates or flat dishes 29. Silverware 30 is disposed in an end section especially provided therefor and preferably lined with a screen 31. The end members 32 of the basket 27 are quite close to the container ends 16 and are sufficiently high to form a support for the tray 33 especially adapted to receive cups 34 and glassware 35.

The operation of the device is as follows: Assuming that a suitable supply of cleansing compound and water 36 have been placed in the sink 37 and that the dishes have been placed within the basket 27 and tray 33 and that the container is placed in the position shown in Figs. 1 and 2, the motor 24 is now started causing air to be drawn up through the opening 22 and discharged from the outlets 26—A.

What actually transpires is this: The water 36 is drawn up into the container until the seal is broken at one side or the other of the container. Assuming that it is first broken at the bottom of the rear wall 11, the water and air rush up in the general direction indicated by the arrows 38, causing an accumulation to take place at the rear of the wall 11 under which it entered the container. The continued operation of the fan will again cause the water to rise and the seal to break under the front wall 10 before the excessive water behind the rear wall 11 has a chance to return to its natural level. The reason the water breaks first under the wall 10 or the wall 11 is because it is almost impossible to have a perfect balance of levels between the edges 19. Also, the position of the dishes and the action of the air discharging through the outlets 26A and 55

other factors affect the action so as to favor one side or the other. Even if the first movement were uniform, that is, if the seal were broken at opposite sides at the same time, the very passage of the water into and out of the container would set up this unbalance.

The net result of this action is to cause a continued reciprocation of the water back and forth through the container along the faces of the dishes 29, and up, under and around the dishes within the tray 33.

Attention is drawn to Patent No. 1,983,931, over which this device is an improvement.

It will be noted in Fig. 3 that the end walls 16 extend to the sink engaging line approximately to the point where the curvature of the corners 39 begins, that is, where the curves 39 are tangent to the sides 16. The exact points, however, where the lowermost part of each wall 16 ends is dependent upon several factors, namely the proportion of the various container dimensions, the distance between the lowermost edges 19 and the sink bottom 18, the capacity of the fan 23, the amount of water used and other factors, it being mainly important that the lateral seals on the under edge of the container are more easily broken than are the end walls, in order that the desired surging action resulting therefrom be normal to the sides 10 and 11 and as nearly as possible uniform along the entire length of the container.

I claim:

1. A dish washer comprising a kitchen sink in combination with an elongated rectangular container having a completely open under side, the bottom edges of the opposite longer sides of the container being spaced from the bottom of the sink and being higher than are the opposite bottom edges of the shorter sides of the container, and means for exhausting air from the upper end of the container which is otherwise closed and discharging same downwardly along the outer sides of the shorter sides.

2. A dish washer comprising a kitchen sink in combination with an elongated rectangular container having a completely open bottom and a closed top, the upper portions of whose longitudinal sides slope inwardly in a manner to make the upper portion of the container narrower than the bottom thereof, means for exhausting air from the closed upper portion of the container, and rubber feet extending along the shorter sides for supporting said container so that the two op-

posite longer sides thereof are held in spaced relation from the bottom of the sink while the opposite shorter edges form the support for the container.

3. A container for dish washers consisting of an elongated box structure having a completely open under side and having the under edges of the elongated side walls at a higher elevation than the corresponding edges of the shorter end walls, and means for evacuating air from the upper portion of the box structure. 5

4. The combination of a sink with the container described in claim 3 in combination with a dish holding basket in said sink over which the container extends, said basket having means for 15 holding flat dishes in substantial parallelism with the shorter ends of the container.

5. A container for dish washing machines consisting of an open bottom rectangular box having one pair of opposite sides forming a support 20 therefor and the other pair of sides having their lower edges spaced from the supporting surface, means for evacuating air from the top side of the box, and ducts for returning the evacuated air downwardly along the outer sides of the box 25 supporting sides. 20

6. The combination of a sink including the container described in claim 5 with a dish holding basket in the bottom of the sink within the container, said basket having compartments for holding flat pieces in parallelism with the supporting walls of the box, and having a tray for supporting cups in an inverted position and elongated tumblers with their mouth ends below their 35 opposite ends. 30

7. A dish washer comprising a kitchen sink in combination with an elongated rectangular container having a completely open under side, the bottom edges of the opposite longer sides of the container being spaced from the bottom of the sink and being higher than the opposite bottom edges of the shorter sides of the container, the length of the sink engaging portions of the shorter sides being less than the distance between the longer sides and means for exhausting air from 40 the upper portion of said container. 45

8. The washer described in claim 7 characterized by having the means for drawing air from said container discharging downwardly along the shorter ends thereof above the lower edge of the 50 container.
